UNITED STATES PATENT OFFICE.

SAMUEL PEACOCK, OF CHICAGO, ILLINOIS.

ELECTRIC FURNACE.

1,090,107.

Specification of Letters Patent.

Patented Mar. 10, 1914.

Application filed September 7, 1912. Serial No. 719,158.

To all whom it may concern:

Be it known that I, SAMUEL PEACOCK, a citizen of the United States, residing at Chicago, in the county of Cook and State of

Illinois, have invented certain new and useful Improvements in Electric Furnaces; and I do hereby declare the following to be a full, clear, and exact description of the invention, such as will enable others skilled 10 in the art to which it appertains to make and use the same.

This invention relates to electric furnaces especially adapted for the production of carbo-nitrids, and has for its object to produce a furnace of this nature which will be more efficient in action and simpler in construction than those heretofore proposed.

To these ends, the invention consists in the novel details of construction and combinations of parts more fully hereinafter disclosed and particularly pointed out in the claim.

Referring to the accompanying drawings forming a part of this specification, in 25 which the figure is a diagrammatic illustration of a furnace made in accordance with my invention, 1 indicates any suitable furnace walls, but preferably provided with a carborundum lining 2, and an outer metallic 30 casing 3.

4 represents a water jacket, surrounding a lower extension of the casing 3, located in a cavity 5 between the brickwork supports 6, and 7 represents inlet and outlet tubes for 35 the said jacket 4.

8 and 9 represent two horizontal electrodes entering the high temperature zone of the furnace, and 10 represents an adjustable electrode adapted to coat with the electrodes 40 8 and 9.

11 represents the charge, generally consisting of a metallic oxid and carbon, and preferably briqueted.

12 represents gas-tight pipes or passages 45 for feeding the charge into the furnace, and 13 represents a pipe for admitting gaseous nitrogen or producer gas to the furnace.

14 represents a pipe leading to a manometer for ascertaining the pressure on the 50 interior of the furnace, and 15 represents a suitable conveyer for continuously removing the products from the furnace.

16 represents an exit, suitably closed by

means not shown, through which the products pass, and 17 represents a means for adjusting the electrode 10 to and from the electrodes 8 and 9.

18 represents a hood for supporting the adjusting means 17 and electrode 10, and is provided with a hand-hole 19, through 60 which access may be had to the furnace.

20 represents a pipe communicating with the lower extension of the furnace for drawing off the furnace gases.

The operation of my furnace is as follows:—The electrode 10 is adjusted quite close to the electrodes 8 and 9, and the furnace is suitably charged with a mixture of say magnesium oxid and carbon. Gas, such as free nitrogen or producer gas, is now 65 admitted through the pipe 13, and current is turned on. Since the electrodes are quite close together, the resistance of the charge is small, and therefore a large amperage may pass. This has the effect of heating 70 up that portion of the charge which is immediately adjacent the electrodes, and rendering same conductive. As the charge becomes heated and conductive, the electrode 10 is gradually withdrawn until a considerable portion of the charge is rendered 75 conductive, and the reaction proceeds over a larger area. As the carbo-nitrid is thus formed, it passes by gravity down through the water jacket 4, and is there gradually 80 cooled, still in an atmosphere of nitrogen, or in an inert atmosphere. After the product is sufficiently cooled, the conveyer 15 removes the same through the exit 16. Since the charge may be continuously fed in 85 through the pipes 12, and the product may be continuously removed from the furnace, it is obvious that the process may be carried on without substantial interruption.

When producer gas is used, its contained 95 nitrogen is being constantly removed through the reactions taking place, and its contained carbon monoxid is being constantly enriched through the carbon monoxid liberated by said reactions, and therefore the producer gas withdrawn through the pipe 20 will be of a greatly improved 100 quality over that admitted through the pipe 13.

The fittings are such that the whole furnace is substantially air and gas tight, as

shown, since it is very desirable that no free oxygen, carbon dioxid CO_2 , or water vapor enter the reaction zone.

What I claim is:—

- 5 In an electric furnace the combination of a plurality of electrodes; means comprising a hand wheel and stuffing box for adjusting one of said electrodes; air tight means comprising two pipes closed at their outer ends
- 10 for introducing charge material; air tight means comprising a valved pipe for introducing gas; a refractory lining tapered in cross section and providing a tapered vertical chamber; an outer air tight casing hav-

ing an extension; a pipe for carrying off 15 gases from said extension; a water jacket carried by said extension concentric with said chamber located below the high temperature zone of the furnace; and conveyer means for continuously removing the product from the furnace as fast as it is formed, substantially as described.

In testimony whereof, I affix my signature in presence of two witnesses.

SAMUEL PEACOCK.
